STORE FRONT

Fred Edward Stuhr, New York, N. Y.

Application January 21, 1952, Serial No. 18,131

Term of patent 3½ years

(Cl. D13—1)

To all whom it may concern:

Be it known that I, Fred Edward Stuhr, a citizen of the United States, residing at New York, in the county of New York and State of New York, have invented a new, original, and ornamental Design for a Store Front, of which the following is a specification, reference being had to the accompanying drawing, forming part thereof.

In the drawing:

Fig. 1 is a front elevational view of a store front, showing my new design;

Fig. 2 is a vertical sectional view, taken on the line 2—2 of Fig. 1; and

Fig. 3 is a horizontal sectional view, taken on the line 3—3 of Fig. 2.

I claim:

The ornamental design for a store front, as shown.

FRED EDWARD STUHR.
